UNITED STATES PATENT OFFICE.

HARRY L. WRIGHT, OF CHICAGO, ILLINOIS.

ADVERTISING DEVICE.

No. 833,432.

Specification of Letters Patent.

Patented Oct. 16, 1906.

Application filed June 22, 1905. Renewed July 24, 1906. Serial No. 327,579.

To all whom it may concern:

Be it known that I, HARRY L. WRIGHT, a citizen of the United States, and a resident of Chicago, in the county of Cook and State of Illinois, have invented certain new and useful Improvements in Advertising Devices, of which the following is a specification.

This invention relates to advertising devices.

The objects of the invention are, first, to convert a roll of toilet-paper into an advertising medium, and, second, to provide means, in connection with a holder for a roll of toilet-paper, whereby as the paper is drawn from said roll an advertisement will be impressed thereon.

My invention consists of the various features, combinations of features, and details of construction hereinafter described and claimed.

In the accompanying drawings, in which my invention is fully illustrated, Figure 1 is a side view, partly in section and with one side thereof removed, of a holder for a roll of toilet-paper embodying my invention, also showing a roll of toilet-paper in operative position therein; and Fig. 2 is a sectional view of the holder, showing the roll and operative parts of the device in elevation.

Referring now to the drawings, 1 designates a holder for a roll of toilet-paper, and 2 a roll of toilet-paper revolvably mounted therein, so that it may be drawn off, as desired, for use.

As shown, the holder 1 is made in the form of a closed box or casing and is provided with a removable side 3 to render the interior of the holder accessible for assembling the operative parts thereof and also for placing the rolls of paper therein as they are used. The holder 1 may be secured to any convenient support by means of screws 4, inserted through the back thereof into said support or in any other desired manner.

The roll of paper preferably consists of a continuous web and is designed to be severed by means of a suitable knife or cutter 5, secured to the exterior of the box or casing 1 and being preferably provided with a serrated or saw edge. Any other desired or approved form of cutter may, however, be employed.

The advertising matter is impressed upon the web, being preferably embossed thereon, by means of combined feed and embossing rollers 6 and 7, mounted in suitable position in the box or casing 1. As shown, said rollers are revolvably mounted one above the other,

directly beneath the roll of paper 2, the upper roll 6 being the platen-roll, and the lower roll 7 the impression or embossing roll. The web of paper (designated by *a*) passes from the roll 2 between the rollers 6 and 7 and thence through a suitable delivery-opening 8, provided in the side of the casing. The severing knife or cutter will of course be located with reference to the delivery-opening 8. 65

Formed on the surface of the impression or embossing roller 7 are raised characters 9, corresponding to the advertisement which it is desired to impress in the web of paper *a*. For convenience in manufacture and to insure requisite strength, rigidity, and durability the outer position of the roller 7, in which said characters are formed, as also the characters 9 themselves, are made of suitable cast metal, preferably aluminium, and to secure desired lightness the position of said roller 7, containing the characters 9, is made in the form of a shell 11, which is secured to an inner wooden core 12, secured to the shaft 13, on which said roller is supported. 75

To secure the desired embossing action of the characters 9, the surface of the platen-roller 6 is made yielding. Said roller preferably consists of an inner wooden core 14 and an outer rubber covering 15. 80

To provide for adjusting the tension of the rollers 6 and 7 upon the web of paper *a* and also the strength of the impression of the characters 9, said rollers 6 and 7 are preferably adjustable toward and from each other. 90 As shown, the roller 7 is mounted in fixed bearings and the roller 6 in adjustable bearing-blocks 16, which are fitted to and freely movable toward and from the roller 7 in suitable guide slots or ways 17, formed in brackets 18 on the inner sides of the box or casing 1. The roller 6 is urged yieldingly toward the roller 7 by means of springs 19, which bear upon the tops of the bearing-blocks 16, the tension of which is adapted to be adjusted by means of screws 20, threaded through the tops of the brackets 18. 95

Rotation is adapted to be imparted to the impression-roller 7 by means of a crank 21, applied to the end of the shaft of said roller, and in order to insure against sticking and stopping of the roller 6 the shafts of the rollers 6 and 7 are preferably connected by gears 22 and 23, secured thereto. Preferably, also, the rollers 6 and 7 are made of different sizes, so that the roller 6 will receive the impressions of the characters 9 on the roller 7. 105 110

in different places, thus materially increasing the life of said roller 6.

A further advantage of forming the characters 9 on a shell is that with this construction the shell may be quickly removed and replaced when it is desired to change the advertisement thereon.

In Fig. 2 the letters *a'* represent the impression of the characters 9 on the roller 7, 10 embossed on the web of paper *a*.

Obviously turning the rollers 6 and 7 in the proper directions will operate to draw the web of paper *a* from the roll 2 and to deliver it through the opening 8 and at the same 15 time to emboss the characters 9 on said web.

I claim as my invention—

1. An advertising device, comprising a roll of toilet-paper, a frame or holder in which said roll is revolvably supported, impression- 20 rollers between which the web of paper passes from said roll, gears which connect the shafts of said impression-rollers and a crank for rotating said rollers.

2. An advertising device comprising a roll 25 of toilet-paper, a frame or holder in which said roll is revolvably supported, impression-rollers of different sizes between which the web of paper passes from said roll, gears which connect the shafts of said impression- 30 rollers and a crank applied to the shaft of one of said rollers.

3. An advertising device, comprising a roll of toilet-paper, a frame or holder in which said roll of paper is revolvably supported, im- 35 pression-rollers between which said web of paper passes from said roll, means to adjust the contact of said rollers, gears which connect the shafts of said rollers and a crank for rotating said rollers.

4. An advertising device, comprising a roll 40 of toilet-paper, a frame or holder in which said roll of paper is revolvably supported, rollers between which the web of paper passes from said roll, said rollers comprising a platen-roller having a yielding surface and an impression-roller having a hard surface and characters embossed thereon, gears which connect said rollers and a crank for rotating one of said rollers.

5. An advertising device comprising a roll 50 of toilet-paper, a frame or holder in which said roll of paper is revolvably mounted, rollers between which the web of paper passes from said roll, one of said rollers having a yielding surface and the other comprising a 55 removable shell of hard material having characters embossed thereon, means to adjust the contact of said rollers, gears which connect said rollers and a crank for rotating said rollers.

6. An advertising device comprising a roll of toilet-paper, a frame or holder in which said roll is revolvably supported, rollers of different size between which the web of paper passes from said roll, one of said rollers having a yielding surface and the other a removable metal shell having characters embossed thereon, means to adjust the contact of said rollers, gears which connect said rollers and a crank for rotating said rollers.

In testimony that I claim the foregoing as my invention I affix my signature, in presence of two subscribing witnesses, this 19th day of June, A. D. 1905.

HARRY L. WRIGHT.
